CIGARETTE HOLDER OR SIMILAR ARTICLE

William R. Holden, 2109 Pullman Lane,
Redondo Beach, Calif. 90278

Filed Dec. 8, 1970, Ser. No. 26,354

Term of patent 14 years

Int. Cl. D27—02

U.S. Cl. D85—8

FIG. 1 is a perspective view of a cigarette holder or similar article showing my new design;

FIG. 2 is a side elevational view showing the side opposite that seen in FIG. 1.

FIG. 3 is a top plan view; and

FIG. 4 is a bottom plan view thereof.

I claim:

The ornamental design for a cigarette holder or similar article, substantially as shown.
